Primary Examiner—Mitchell Siegel*(74) Attorney, Agent, or Firm*—Oliff & Berridge, PLC**(57) CLAIM**

The ornamental design for a golf club head, as shown and described.

DESCRIPTION

FIG. 1 is a bottom perspective view of a golf club head, embodying the inventive design.

FIG. 2 is an orthographic bottom plan view thereof.

FIG. 3 is an orthographic heel side elevational view thereof; and,

FIG. 4 is an orthographic rear elevational view thereof.

The broken lines represent the environmental elements only; the broken lines form no part of the claimed design.
